HYDRAULIC FLUID VOLUME COMPENSATOR

Herman Ray Ellinwood, Burbank, Calif., assignor to Adel Precision Products Corp., a corporation of California

Application November 24, 1942, Serial No. 466,783

6 Claims. (Cl. 60—54.5)

This invention relates to hydraulic motor systems, particularly hydraulic systems for operating the controls and component mechanisms of aircraft and the like.

A primary object of my invention is to provide a hydraulic fluid volume compensator which in a most reliable and efficient manner will fully compensate for thermal expansion and contraction and volumetric variations of the hydraulic fluid in a hydraulic system to insure the presence in all working parts of the system of the requisite amount of hydraulic fluid for a reliable operation of the system at all times.

Another object of my invention is to provide an improved hydraulic motor system embodying a volume compensator of the character described which is inoperative while the system is in operation and rendered operative upon cessation of operation of the system.

A further object of my invention is to provide an efficient manually operable motor system such as described in which a flow reversing pump unit is operable for directing fluid to actuate a hydraulic motor in either direction, and the volume compensator of my invention is rendered inoperative by and upon the act of releasing from a normally locked position a lever for actuating the pump unit, and rendered operative immediately following the locking of said lever and the cessation of operation of the pump unit.

Yet another object of my invention is to provide a hydraulic fluid volume compensator in which a compensator chamber and a diaphragm means therein, together with a valve means, are arranged so that there is formed an expandable and contractible reservoir means and a pressure compartment, said reservoir means being connected through the valve means to both sides of hydraulic system, and said pressure compartment containing a fluid under a pressure to which the diaphragm means is responsive whereby hydraulic fluid will be forced from as well as into said reservoir means incident to volume variations in the system caused by thermal expansion and contraction of the fluid therein as well as by leakage, the said valve means being arranged to render the compensator inoperative upon operation of the system and operative when the system ceases to operate.

Yet another object of my invention is to provide a volume compensator of the character described in which a chamber and a diaphragm means are arranged to define expandable and contractible compartments, two of which are reservoir compartments adapted to be connected to the

hydraulic lines of both sides of a hydraulic motor system and one of which, located between said two compartments, contains a compressible fluid under a predetermined pressure to which the diaphragm means is responsive as well as to the fluid pressure in said system lines, thereby insuring the flow of fluid into and from said reservoir compartments to maintain the proper amount of fluid throughout the system.

10 With the foregoing objects in view, together with such other objects and advantages as may subsequently appear, the invention resides in the parts and in the combination, construction, and arrangement of parts hereinafter described and claimed, and illustrated by way of example in the accompanying drawings, in which:

Fig. 1 is a diagrammatic view of a hydraulic system embodying my invention;

Fig. 2 is a diagrammatic view of a modified form 20 of system embodying my invention.

Fig. 1a is an end elevation of the upper part 15 of the structure shown in Fig. 1 looking from right to left as indicated by the arrows 1a on Fig. 1.

Referring to the drawings more specifically, it 25 is seen with reference to Fig. 1 that a hydraulic system embodying my invention generally includes a hydraulic pump unit A operable manually to direct hydraulic fluid through lines B and C to opposite sides of a motor D employed, for example, to actuate the control elements or component mechanisms of an aircraft.

A compensating accumulator unit E is connected to the lines B and C through the instrumentality of valve means F which is controlled 35 by an operating means G operatively associated with a lever locking means H of a lever J for operating the pump unit. This arrangement is such that the operation of releasing the locking means H causes the valve means F to be closed and the compensating unit E to be rendered inoperative 40 but when the locking means is locked and the pump unit thereby made inoperative, the valve means is opened so that in case of expansion of the fluid in the system the fluid will be relieved to the compensator unit E and in case of contraction 45 or leakage of the fluid in either or both sides of the system, the compensator unit will automatically force fluid into the system to compensate for the loss of volume resulting from such contraction or leakage.

As here shown the pump unit includes a cylinder 1 in which a piston 2 is reciprocable to force fluid from the cylinder to operate the motor unit D in either direction. The lever J is suitably 55 crimped on a pivot one end as at 3, and has a pin

and slot connection 4 with the piston 2, there being slots 5 and 6 in the cylinder 1 to accommodate the lever. The motor unit as here shown includes a cylinder 7 having a reciprocable piston 8 therein and provided with a drive means 9 operated by a rack 10 formed on the piston.

As here provided the locking means H for lever J includes a notched quadrant 11, a locking rod 12 reciprocally supported on the lever to slide longitudinally therealong and having a bolt portion 13 thereon adapted to be engaged in the notches in the quadrant 11. This locking rod 12 is normally urged into locking position by means of a spring 14 in the valve operating means G and is depressed to release the lever, which has a slotted part in a slidable relation to the pivot 3. On depressing the locking rod 12 the inner end 15 thereof forces a plunger 16 inwardly in a support 17 therefor against the action of the spring 14. The spring 14 is contained in a tubular guide member 18 slidably in the support 17 and receiving the inner end of the plunger 16. A cross head 19 on the inner end of the guide member 18 is provided with a guide pin 20 slidable in a bore 21 of a valve body member 22. In this body member 22 are valve chambers 23 and 24 having valve seats 25 and 26 between ports 27 and 28. Poppet valves 29 and 30 are mounted in the chambers 23 and 24 respectively and have their stems 31 fixed to the cross head 19. Springs 32 for these valves normally hold the valves open and assist the spring 14 in urging the lever-locking means into locking position.

A fluid line 33 connects line B with the valve chamber 23 through one of the ports 27 whereas a fluid line 34 connects the line C with the valve chamber through the other port 27. The ports 28 are provided for affording communication of the valve unit with the compensating unit E.

In accordance with my invention the compensator unit is designed to provide a fluid filled expansible and contractible reservoir means and a pressure means therein. The reservoir means is adapted to be connected to both sides of the system through the valve means F for receiving fluid from and supplying fluid to said sides of the system. The pressure means, for example, may be provided as a compartment containing air trapped therein under a predetermined pressure such that the reservoir means is responsive thereto as well as to the pressure of the hydraulic fluid in the system. The arrangement is such that when the system is not under operation the valve means is opened and if the fluid in any part of the system contacts or leaks out, thereby reducing the volume of the operating fluid, the pressure of the hydraulic fluid in the reservoir means of the compensator unit is reduced below that of the air pressure in the pressure compartment and the reservoir means then contracts and forces fluid therefrom into the system in full compensation for the volume loss caused as aforementioned. In case of expansion of fluid in any part of the system the resultant increased pressure causes the reservoir means to expand as permitted by the compression of the air in the pressure compartment, whereby the excess volume is relieved from the system into said reservoir means and an effective volume compensation is thus produced throughout the system.

As shown in Fig. 1 the compensator means E includes a closed chamber 35 having diaphragms 36 and 37 arranged therein to define expansible and contractible reservoir compartments 38 and 39 separated by a pressure compartment 40 which

fills in the space between said reservoir compartments. Lines 41 and 42 connect the ports 28 in the valve body member 22 with the reservoir compartments 38 and 39 respectively. This arrangement constitutes a reservoir means in accordance with this invention, as hereinbefore noted.

The pressure compartment is provided with a valved inlet 43 whereby the compartment may be supplied with a compressible fluid such as air under a predetermined pressure to which the diaphragms 36 and 37 will be responsive in case the fluid in the system contracts or leaks out to an extent that the pressure of such fluid is below that of the air in the pressure compartment.

It is now apparent that when the operator depresses the rod 12 for releasing the locking means H for the lever J, the inner end 15 of said rod will depress the plunger 16, and through the spring 14 likewise depresses the tubular guide 18, cross head 19, and the valves 29 and 30, thereby closing the valves. It should be noted that before the locking bolt 13 on the rod 12 releases the lever J the valves 29 and 30 will be seated to insure that the valves are closed before the pump unit A is operated. Thus the compensator unit E is rendered inoperative during operation of the pump and motor units.

When the operator releases the locking rod 12 the locking bolt 13 thereon locks the lever to the quadrant and the valves 29 and 30 are released so that the springs 32 will unseat them, thereby rendering the compensator unit E operable. At this time if the hydraulic fluid in the system contracts or leaks out to the extent that the pressure thereof is below that of the air in the pressure chamber 40, the diaphragms 36 and 37, either one or both thereof, depending on whether the pressure reduction occurs in one or both sides of the system, will respond to the air pressure so that fluid will be forced into the system from either or both of the compartments 38 and 39 into the system to compensate for the volume loss due to said contraction or leakage.

It is to be observed that the inner end portion 15 of the locking rod 12 terminates in a curved surface which affords a continuous contact of said rod with the plunger 16 of the valve means in all the operative angular positions of the swingable lever J.

It will also be seen that the spring opposed slidable rod 12 carried by the lever is slidable therealong by a hand of the operator which is thereupon positioned to swing said lever while maintaining said rod in the position to which it has been slid. Therefore the operator can, by the use of single hand swing the lever through its entire range of movement while maintaining the valves closed and the compensating system hydraulically isolated from the conduits which connect the driving and driven units.

In case of expansion of the fluid in the system the pressure of the hydraulic increases and expands the compartments 38 and 39 or either thereof depending on whether the expansion occurs in one or both sides of the line, the air in compartment 40 then compressing. This allows the excess of fluid produced by such expansion to be relieved into the compartments 38 and 39 or either thereof and the desired volume is provided in both sides of the system to insure a proper operation thereof.

As shown in Fig. 2, a modified form of my invention includes a pump unit A', lines B' and C' leading therefrom to a motor unit D', a modified form of compensating accumulator unit E', a

valve means, F', a valve operating means G', a lever locking means H' and a lever J'. With the exception of the compensator unit E' all of the other elements of this system are identical with the corresponding elements of the first described system as shown in Fig. 1.

In this modified form the unit E' includes a chamber 58 having a single diaphragm 51 therein defining a reservoir means such as the compartment 52 and a pressure means such as the compartments 53. The reservoir compartment 52 is connected by branched lines 54 and 55 with the valve chambers 56 and 57 containing the valves 58 and 59. This makes the two lines B' and C' of the system subject to communication through the valve means with the single reservoir compartment 52.

The pressure compartment 53 has a valved inlet 60 whereby it may be charged with air under a predetermined pressure to which the diaphragm is responsive when thermal contraction of the fluid in the system takes place, for forcing fluid from the reservoir chamber into the system in the same manner as in the other form of my invention. In case of thermal expansion of the fluid in the system the reservoir compartment 52 will expand by action of the diaphragm and compensate for the excess pressure and volume.

I claim:

1. In a hydraulic motor system, a pump unit, a motor unit, hydraulic lines for conducting fluid between said units to operate said motor unit, a lever for operating said pump unit, a lever locking means including a rod carried by said lever and slidably longitudinally therealong, a hydraulic fluid volume compensating means connected with lines, a valve means for controlling the operation of said compensating means, and means operating responsive to the release of said locking means by a sliding movement of said rod, for closing said valve means and rendering the compensating means inoperative, and for opening said valve means and rendering the compensating means operative when the locking means is manipulated to lock said lever and render the pump unit inoperative.

2. In a hydraulic motor system, a pump cylinder having a piston head in each of opposite end portions, a lever swingably mounted between said piston heads and operatively connected with them to reciprocate them simultaneously, means carried by said lever to release and to lock it including a manually operable rod slidably lengthwise therealong, a pivot to which one end portion of said lever is fulcrumed and with which said rod is slidably connected, a toothed locking segment for said lever into and out of engagement with which said rod is manually movable owing to its said slidable mounting, a motor unit, drive means connected therewith and operable in opposite directions by fluid pressure delivered to said motor, a hydraulic line leading from one end portion of the aforesaid piston cylinder to said motor unit to move said drive means in one direction, a hydraulic line leading from the opposite end portion of said piston cylinder to said motor unit to move said drive means in the opposite direction, a hydraulic compensating means connected with said lines, a valve means for controlling the operation of said compensating means, and means operating in response to the sliding movement of said rod for closing said valve means and rendering the compensating means inoperative, and for opening said valve means and rendering the compensating means operative when the locking

means is manipulated to lock said lever and render the pump cylinder inoperative, the inner end portion of said slidable rod having a curved surface which affords a continuous contact with a part of said valve means in all positions of said swingable lever, said valve means including a spring which maintains it in continuous contact with said curved surface of said rod.

3. The subject matter of claim 2, and said valve means including a reciprocatory plunger which is urged in one direction by said spring and is at times moved in the opposite direction by the action thereon of said curved portion of said rod.

4. In a hydraulic motor system, a pump cylinder having a piston head in each of opposite end portions, a lever swingably mounted between said piston heads and operatively connected with them to reciprocate them simultaneously, means carried by said lever to release and to lock it including a manually operable rod slidably lengthwise therealong, a pivot to which one end portion of said lever is fulcrumed and with which said rod is slidably connected, a toothed locking segment for said lever into and out of engagement with which said rod is manually movable owing to its said slidable mounting, a motor unit, drive means connected therewith and operable in opposite directions by fluid pressure delivered to said motor, a hydraulic line leading from one end portion of the aforesaid piston cylinder to said motor unit to move said drive means in one direction, a hydraulic line leading from the opposite end portion of said piston cylinder to said motor unit to move said drive means in the opposite direction, a hydraulic compensating means connected with said lines, a valve means for controlling the operation of said compensating means, and means operating in response to the sliding movement of said rod for closing said valve means and rendering the compensating means inoperative, and for opening said valve means and rendering the compensating means operative when the locking means is manipulated to lock said lever and render the pump cylinder inoperative, said valve means being movable in one direction by said rod and being furnished with a spring acting in opposition to said rod to move said valve means in opposite direction.

5. In a hydraulic motor system, a pump unit, a motor unit, hydraulic lines for conducting fluid between said units to operate said motor unit, a lever for operating said pump unit, a locking means for said lever including a spring opposed rod carried by said lever and slidably longitudinally therealong by a hand of the operator which is thereupon positioned to swing said lever while maintaining said rod in the position to which it has been slid, in which position said rod unlocks said lever, a hydraulic fluid volume compensation means connected with said lines, a valve means for controlling the operation of said compensating means, and means operating in response to the aforesaid sliding movement of said rod for closing said valve means thereby rendering the compensating means inoperative, and operable by the spring impelled action of said rod to lock said lever and simultaneously render the compensating means operative.

6. In a hydraulic motor system, a pump unit, a motor unit, hydraulic lines for conducting fluid between said units to operate said motor unit, a lever for operating said pump unit, a spring opposed locking means carried by said lever and movable in relation thereto by a hand of the operator which is at the same time positioned to

swing said lever while maintaining said locking means in the position to which it has been moved, in which position it unlocks said lever, a hydraulic fluid volume compensating means connected with said lines, a valve means for controlling the operation of said compensating means, and means operating in response to the manual actuation

of said spring opposed means for closing said valve means, thereby rendering the compensating means inoperative, and operable by the spring to lock said lever and simultaneously render the compensating means operative.

HERMAN RAY ELLINWOOD.
